UNITED STATES PATENT OFFICE.

SAMUEL W. AVIS, OF WEST HARTFORD, CONNECTICUT.

FEED MECHANISM FOR SEWING MACHINES.

Application filed January 19, 1924. Serial No. 687,351.

This invention relates to the mechanisms provided for feeding the material to be stitched through sewing machines, particularly machines which are designed to be run at high speeds, and it is illustrated as adapted to an over edge machine of the type illustrated and described in my application for Patent #393,223 filed July 1, 1920.

In machines of this character it is desirable not only to be able to change the length of movement of the feed dogs in order to increase or decrease the number of stitches per inch in the material fed, and on account of the nature of the work to be able to have the respective feed dogs travel different distances, but also to be able to vary the travel of the feed dogs with relation to each other while the machine is running.

The object of the invention is to produce a variable differential feed for machines of the class mentioned, which is comparatively cheap to manufacture and assemble, is durable and efficient in operation and is capable of a delicate yet wide range of adjustment without stopping the machine.

In the accompanying drawings Fig. 1 shows a plan of a machine of the type referred to, with the work plate broken away to expose the feed mechanism. Fig. 2 is a vertical longitudinal section of the machine with the improved feed. Fig. 3 is a transverse section taken on the dotted line 3-3 on Fig. 1. Fig. 4 is an elevation of one side near one end. Fig. 5 is an elevation of the other side showing the means provided for effecting the variation of the differential feed. Fig. 6 is a view looking up at the parts shown in Fig. 5. Fig. 7 is a side view of one of the feed dog carriers and the adjustable mechanism for reciprocating it. Fig. 8 is a section of the adjustable feed dog reciprocating mechanism on the line 8-8 on Fig. 7. Fig. 9 is a vertical transverse section taken on the plane indicated by the dotted line 9-9 on Fig. 2. Fig. 10 is a plan of the feed dogs, their carriers, and the oscillatory cradle in which the carriers are slidably mounted. Fig. 11 is a side view of the parts shown in Fig. 10. Fig. 12 is an end view of the same. Fig. 13, is a perspective view of the feed dogs and carriers, the cradle, and the mechanism for oscillating these parts.

In the machine illustrated as described in the application referred to, all of the active mechanisms are operated from a single cam

shaft 1 which is supported below the work plate 2 by the bed block 3 in the casing 4, with its axis parallel to the line of feed of the work to be stitched. On the cam shaft 60 is a cam 5 that through the intermediate mechanism causes the reciprocation of the feed dogs 6 and 7 in a direction parallel with the cam shaft, and on the shaft is a cam 8 that through the intermediate mechanism causes the oscillation of the feed dogs, the feed dogs being advanced with their teeth above the top of the needle plate 9 and then at the limit of the advance movement oscillated so as to carry the teeth below the needle plate, then retracted with the teeth in this lower plane, and finally at the end of their return movement oscillated so as to lift the teeth above the plane of the needle plate, as fully set forth in the prior application mentioned.

The front feed dog 6 is detachably fastened to a carrier slide 10, and the rear feed dog 7 is detachably fastened to a carrier slide 11. The feed dogs may have teeth of any conventional shape and arrangement. The feed dog carriers are fitted together so that they may be reciprocated independently of each other but will fill an opening in an oscillatory cradle 12, in which they are slidable, so that they will oscillate together as one piece on a longitudinal axis when the cradle is rocked. The carriers are shown as triangular in cross section but they may be made in other forms which will slidably fit 85 the opening through the cradle and yet be oscillated by the rocking of the cradle. A cover plate 13 extending across the top of the opening in the cradle retains the carriers in place. The under surface of the cradle is 90 cylindrical and is fitted to a correspondingly shaped cavity in the top of a block 14. In the top of the cover plate is a curved groove 15 that is concentric with the under side of the cradle. Attached to the under side of the needle plate 9 is a strip 16 that fits the curved groove in the cover of the cradle so as to hold the cradle in place. This strip forms the axis upon which the cradle 95 is rocked. When the needle plate is removed 100 the cradle with the carriers and feed dogs is free to be lifted from the casing. When the cover plate is unfastened from the cradle 105 the carriers and feed dogs can be taken out.

The cradle is held from longitudinal 110 movement but is free to be oscillated on a longitudinal axis, and the feed dog carriers

are free to be independently reciprocated through the cradle but are oscillated as one piece with the cradle. The cradle at the front end has a downwardly projecting fork 17 by means of which it may be oscillated. The front feed dog carrier at its front end has a fork 18 projecting outwardly toward one side, by means of which this carrier may be reciprocated and the rear feed dog carrier at its front end has a fork 19 projecting outwardly toward the other side, by means of which it may be reciprocated. The fork 17 on the under side of the cradle contains a shoe 20 on the swinging end of a yoke-shaped lever 21 that is mounted on a pivot stud 22 that is eccentrically mounted in the front side of the bed block 3. The cam 8 on the cam shaft 1 lies in the opening in the yoke 21 so that the rotation of the shaft through this cam will at the correct times oscillate the lever and rock the cradle which carries the feed dogs. The fork 18 at the front end of the front feed dog carrier is occupied by a shoe 24 on the upper end of an angle lever 25, and the fork 19 at the front end of the rear feed dog carrier is occupied by a shoe 26 on the upper end of a similar angle lever 27. The oscillations of these levers cause the reciprocation of the feed dog carriers. In order that these levers may be oscillated independently of each other the lever 27 has a tubular arbor 28 and the lever 25 a solid arbor 29 that is fitted within the tubular arbor so that these arbors will be concentric and yet one may turn relatively to the other. The arbors are rotatably mounted in an opening in a block 30 that is fastened to the front end of the block 3. The lower end of the lever 25 has a roll 31 lying in a cam slot 32 in a bell crank plate 33 that has a long tapering arbor 34. The lower end of the lever 27 has a roll 35 lying in a similar slot 36 in a bell crank plate 37 that has a long tapering arbor 38. In radial slots 39 in each of the bell crank plates is a shoe 40 mounted on a stud 41 projecting from the side of a vertically movable yoke-shaped slide 42. The cam 5 on the main shaft lies in the opening in this slide so that the rotation of the shaft through the cam at the correct periods moves the slide up and down and through the bell crank plates oscillates the levers that reciprocate the feed dog carriers. The arbor 38 is eccentrically mounted in a cylinder 43 that is rotatably adjustable in a hub 44 extending inward from one side of the casing, while the arbor 34 is eccentrically mounted in a cylinder 45 that is rotatably adjustable in a hub 46 extending inward from the other side of the casing. By rotatably adjusting these cylinders the angular relations of the axes of the bell crank plates to the axes of the shoes on the yoke which engage and oscillate the crank plates

as the yoke moves up and down, may be changed. In other words by turning the cylinders the radial slots 39 in the bell crank plates may be adjusted more or less angularly toward and from the up and down path of movement of the shoes 40 that are carried by the yoke slide and which lie in the radial slots and oscillate the bell crank plates. By this means the throw of the bell crank plates may be independently varied so as to give the angle levers greater or less oscillating movements and the feed dog carriers more or less travel.

In order to adjust the throw of the rear feed dog carrier the cylinder 43 has a stem 47 that projects outward through a plate 48 fastened to the side of the casing. On this stem is a disk 49 the periphery of which is graduated. When the nut 50 on the stem 47 is loosened the disk 49 may be grasped and turned and the cylinder rotated so as to carry the axis of the bell crank plate 37 to such position that the throw of the plate will cause the desired movement to be imparted to the rear feed dog. When the adjustment has been effected to give the required travel to the rear feed dog the nut 50 is tightened so as to clamp the parts in the positions to which they are adjusted.

In order to effect a variation of the travel of the feed dogs while the machine is in operation the cylinder 45 which carries the arbor 34 of the bell crank plate 33 may be provided with a gear 51 and meshing with this gear may be a pinion 52 on a shaft 53 which projects through a plate 54 fastened to the side of the casing. On the outer end of the shaft is a disk 55 the periphery of which is graduated. Upon turning this disk the shaft is turned and through the gears the cylinder 45 carrying the arbor 34 is rotated. On the shaft outside of the disk is an arm 56. A spring 57 coiled around the hub of the arm has one end engaged with a stud 58 projecting from the plate and the other end engaged with a stud 59 projecting from the inside of the arm. The arm is clamped to the disk by a nut 60. When the arm is turned the disk will be turned so that through the gears the parts will be adjusted to give the front feed dog the desired travel. The arm may be moved by hand or by any other desired means for effecting the adjustment. A stop pin 61 is arranged to project from the plate in position to stop the arm when it is turned back by the spring. Surrounding the shaft between the plate and the disk is an annular plate 62 which has a stop lug 63 and that is clamped in position by a screw 64. This plate is adjusted so the stop lug will be engaged and will stop the cam in the required locality to give the desired distance of travel to the front feed dog. When the arm is released the spring returns it to the normal position. Upon loosening the

nut 60 the handle may be freed from the disk so that the disk may be adjusted to give the normal amount of feed to the front feed dog carrier. After the adjustment has been made and the nut is tightened so as to clamp the handle to the disk the stop plate is adjusted to locate the stop lug in the position which will ensure the same temporary or abnormal amount of feed to the front feed dog. With this mechanism the travel of either feed dog may be changed at will, so that either may be made to go a greater or less distance than the other as desired. Also the difference in the feed of the two feed dogs may be varied, and any adjustment of the relations of the travel of one dog to the other may be effected without stopping the machine.

The invention claimed is:

- 20 1. A feed mechanism for sewing machines, comprising a plurality of reciprocatory feed dog carriers, an oscillatory cradle supporting said carriers, mechanism for reciprocating said carriers independently of said cradle, and mechanism for oscillating said cradle with the reciprocatory feed dog carriers mounted thereon, transversely of the line of feed whereby the feed dogs carried thereby will travel forward in an upper path and will travel backward in a path lower and at one side of the path of forward travel.
- 25 2. A feed mechanism for sewing machines, comprising a reciprocatory front feed dog carrier, a reciprocatory rear feed dog carrier, an oscillatory cradle supporting said carriers, mechanism for oscillating said cradle transversely of the line of feed whereby the feed dogs carried thereby will travel forward in an upper path and will travel backward in a path lower and at one side of the path of forward travel, and mechanism for reciprocating the feed dog carriers independently of said cradle.
- 30 3. A feed mechanism for sewing machines, comprising a reciprocatory front feed dog carrier, a reciprocatory rear feed dog carrier, an oscillatory cradle supporting said carriers, mechanism for oscillating said cradle transversely of the line of feed whereby the feed dogs carried thereby will travel forward in an upper path and will travel backward in a path lower and at one side of the path of forward travel, and mechanism for reciprocating the feed dog carriers independently of each other and independently of said cradle.
- 35 4. A feed mechanism for sewing machines, comprising a reciprocatory front feed dog carrier, a reciprocatory rear feed dog carrier, an oscillatory cradle in which said carriers are slidably fitted, mechanism for reciprocating said carriers independently of said cradle, and mechanism for oscillating said cradle with the reciprocatory feed dog carriers fitted therein, transversely of the line of feed whereby the feed dogs carried thereby will travel forward in an upper path and will travel backward in a path lower and at one side of the path of forward travel.
- 40 5. A feed mechanism for sewing machines, comprising a reciprocatory front feed dog carrier, a reciprocatory rear feed dog carrier, an oscillatory cradle supporting said carriers, mechanism for reciprocating said carriers independently of said cradle, mechanisms for varying the action of said reciprocating mechanism on the respective feed dog carriers, and mechanism for oscillating said cradle with the feed dog carriers mounted thereon, transversely of the line of feed whereby the feed dogs carried thereby will travel forward in an upper path and will travel backward in a path lower and at one side of the path of forward travel.
- 45 6. A feed mechanism for sewing machines, comprising a reciprocatory front feed dog carrier, a reciprocatory rear feed dog carrier, an oscillatory cradle supporting said carriers, mechanism for reciprocating the front feed dog carrier, mechanism for reciprocating the rear feed dog carrier, and means for adjusting said reciprocating mechanism whereby the travel of the feed dog carriers may be varied.
- 50 7. A feed mechanism for sewing machines, comprising a plurality of reciprocatory feed dog carriers, an oscillatory cradle in which said carriers are slidably fitted, mechanism for reciprocating said carriers independently of said cradle, and mechanism for oscillating said cradle with the reciprocatory feed dog carriers fitted therein, transversely of the line of feed whereby the feed dogs carried thereby will travel forward in an upper path and will travel backward in a path lower and at one side of the path of forward travel.
- 55 8. A feed mechanism for sewing machines, comprising a plurality of reciprocatory feed dog carriers, an oscillatory cradle supporting said carriers, mechanism for reciprocating said carriers independently of said cradle, mechanisms for varying the action of said reciprocating mechanism on the respective feed dog carriers, and mechanism for oscillating said cradle with the feed dog carriers mounted thereon, transversely of the line of feed whereby the feed dogs carried thereby will travel forward in an upper path and will travel backward in a path lower and at one side of the path of forward travel.
- 60 9. A feed mechanism for sewing machines, comprising two reciprocatory feed dog carriers, an oscillatory cradle supporting said carriers, an oscillatory cradle transversely of the line of feed whereby the feed dogs carried thereby will travel forward in an upper path and will travel backward in a path lower and at one side of the path of forward travel.
- 65 10. A feed mechanism for sewing machines, comprising a reciprocatory front feed dog carrier, a reciprocatory rear feed dog carrier, an oscillatory cradle supporting said carriers, mechanism for reciprocating the front feed dog carrier, mechanism for reciprocating the rear feed dog carrier, and means for adjusting said reciprocating mechanism whereby the travel of the feed dog carriers may be varied.

carriers, independently adjustable mechanisms for reciprocating said carriers independently of each other and of said cradle, and mechanism for oscillating said cradle 5 with the reciprocatory feed dog carriers mounted thereon, transversely of the line of feed whereby the feed dogs carried thereby will travel forward in an upper path and will travel backward in a path lower 10 and at one side of the path of forward travel.

10. A feed mechanism for sewing machines, comprising two reciprocatory feed dog carriers, an oscillatory cradle in which 15 said carriers are slidably fitted, adjustable mechanism for reciprocating said carriers independently of each other and of said cradle, and mechanism for oscillating said cradle transversely of the line of feed whereby 20 the feed dogs carried thereby will travel forward in an upper path and will travel backward in a path lower and at one side of the path of forward travel.

11. A feed mechanism for sewing machines, comprising two reciprocatory feed dog carriers, said carriers being fitted together and slidably with relation to each other, an oscillatory cradle supporting said carriers, mechanism for reciprocating said 25 carriers independently of said cradle and independently of each other, and mechanism for oscillating said cradle with said feed dog carriers mounted thereon, transversely of the line of feed whereby the feed dogs 30 carried thereby will travel forward in an upper path and will travel backward in a path lower and at one side of the path of forward travel.

12. A feed mechanism for sewing machines, comprising two feed dog carriers, said carriers being fitted together and slidably with relation to each other, an oscillatory cradle with a groove containing said 35 carriers, a removable cover retaining the carriers in said groove, mechanism for oscillating said cradle transversely of the line of feed whereby the feed dogs carried thereby will travel forward in an upper path and will travel backward in a path lower 40 and at one side of the path of forward travel, and mechanism for reciprocating the feed dog carriers independently of each other and said cradle.

13. A feed mechanism for sewing machines, comprising two feed dog carriers 45 slidably with relation to each other, oscillatory means supporting said carriers, mechanism for oscillating said supporting means, mechanisms for reciprocating the feed dog 50 carriers independently of each other and independently of said supporting means, and adjustable means for varying the action of one of the feed dog reciprocating mechanisms, said adjustable means including gears 55 and means for rotating said gears.

14. A feed mechanism for sewing machines, comprising two feed dog carriers slidable with relation to each other, an oscillatory cradle supporting said carriers, mechanism for oscillating said cradle transversely of the line of feed whereby the feed dogs carried thereby will travel forward in an upper path and will travel backward in a path lower and at one side of the path of forward travel, mechanism for reciprocating 70 the feed dog carriers independently of each other, adjustable means for varying the action of both of said reciprocating mechanisms, one of said means including an operating arm by which the adjustment may be obtained while the machine is running. 75

15. A feed mechanism for sewing machines, comprising two feed dog carriers slidable with relation to each other, an oscillatory means supporting said carriers, 80 mechanism for oscillating said supporting means, mechanism for reciprocating the feed dog carriers independently of each other and the supporting means, and adjustable means for varying the action of the feed dog 85 reciprocating mechanisms, one of said adjustable means including a spring controlled operating arm, and stops for limiting the movements of said arm, whereby the action of one of said reciprocating mechanisms may 90 be varied from normal and then returned to normal. 95

16. A feed mechanism for sewing machines, comprising a reciprocatory front feed dog carrier, a reciprocatory rear feed dog 100 carrier, and a sidewise oscillatory cradle in which said carriers are slidably supported and by which they are oscillated sidewise at the ends of their reciprocatory movements about an axis parallel to the direction of feed, said supporting means and the carriers being assembled in and removable from the machine as a unit.

17. A feed mechanism unit for sewing machines, comprising two independent reciprocatory feed dog carriers, and a cradle supporting said carriers, said cradle mounted to oscillate transversely of the line of feed of the feed dog carriers and said carriers being fitted together and slidably fitting an 110 opening in said cradle. 115

18. A feed mechanism for sewing machines, comprising two feed dog carriers slidably with relation to each other, an oscillatory means supporting said carriers, mechanism for oscillating said supporting means, mechanism for reciprocating the feed dog carriers independently of each other and the supporting means, and adjustable means for varying the action of the feed dog reciprocating mechanisms, one of said adjustable means including an operating arm, and an adjustable stop for limiting the movement of said arm, whereby the action of one of said reciprocatory mechanisms may be 120 125 130

varied from a desired normal and returned to normal.

19. In combination with the needle plate of a sewing machine, of a feed mechanism comprising a reciprocatory front feed dog carrier, a reciprocatory rear feed dog carrier, an oscillatory cradle supporting said carriers, the axis of oscillation of said cradle

being at the under side of the needle plate and extending parallel with the line of feed, 10 feed dogs attached to the carriers at one side of said axis of oscillation of the cradle, and means for reciprocating the feed dog carriers and oscillating the cradle.

SAMUEL W. AVIS.
